UNITED STATES PATENT OFFICE

FRED E. DALRYMPLE, OF MILFORD, NEW YORK

MAIL-BOX SUPPORT

Application filed October 17, 1929. Serial No. 400,300.

This invention relates to deposit and collection mail receptacles and has more particular reference to an improved means for supporting the same.

5 A still further object of the invention is to provide an improved support especially designed for supporting mail boxes which will be of an inexpensive and durable character, embodying novel features of adjustment whereby various standard types of mail boxes may be supported thereon.

10 Other objects and advantages of this invention will become apparent during a study of the following description taken in connection with the accompanying drawings, wherein:

15 Figure 1 is a side elevation, partly in section of the improved mail box support, parts of the post being shown in section,

20 Figure 2 is a horizontal detail sectional view taken substantially on line 2-2 of Figure 1,

25 Figure 3 is a fragmentary front elevation of the supporting post at the upper end portion of the post.

With reference more in detail to the drawings, it will be seen that the numeral 5 designates generally an elongated tubular vertical post, its lower end inserted in the ground 30 and having its upper end slidably receiving one end of an adjustable member 6.

The adjustable member 6 is in the nature of a curved tube of sufficiently small diameter to move freely in the inside of the tube 5. 35 The tube or member 6 consists of an upright leg or shank 7 fitting into the tube 5, and the laterally extending curved end portion 8, to the outer extremity of which is secured by suitable brackets 9 and 10 respectively a conventional mail box 11.

40 The tubular member 5 is provided on its upper portion and on three sides thereof with a longitudinally extending slot 12. In forming the respective slots 12, the tube 5 at its upper end portion is bowed or pressed outwardly as at 13 the opposite sides thereof, and along the front side, so as to provide three of such slots 12.

45 The leg 7 of the member 6 intermediate its ends has one side thereof pressed outward-

ly as at 14 to provide a laterally extending lug 15 adapted to be selectively received in either of the grooves 12.

In practice, the member 6 may be rotated or turned so that its curved portion 8 will extend directly forward of the tubular post 5 or to either side of the post, thus bringing the lug 15 into seated position within one of the grooves 12, after which the leg 7 of the member 6 may be slid longitudinally down into the post 5, the lug 15 riding in that groove depending upon the direction with respect to the post 5 that the curved arm 8 of the member is to extend.

In practice, the intermediate or front 65 groove 12 will be the street line and the lug 14 may be received in this intermediate groove 12 in order that the mail box 11 carried on the curved portion 8 of the member 6 will be disposed within convenient reach of the postman delivering the mail, after which it may be swung to either the right or left inwardly from the street line so as not to interfere with passersby.

70 It is believed that from the foregoing description, a clear understanding of the operation, construction, utility and advantages of the device of this nature will be had by those skilled in this art. A more detailed description thereof is believed unnecessary.

75 Having thus described my invention, what I claim as new is:

80 A mail box support comprising a hollow tubular supporting post provided with a plurality of longitudinally extending struck out reinforcing ribs, the ribs defining internal locking grooves, and a supporting rod insertable in the tube and rotatable therein having a stop collar resting on the upper edge of the post, with a struck out lug formed 85 therein for selective engagement in any one of said locking grooves.

90 In testimony whereof I affix my signature.

FRED E. DALRYMPLE.
